UNITED STATES PATENT OFFICE.

JAMES POLLOCK, OF NEW YORK, N. Y.

FURNACE FOR BURNING FINE FUEL.

Application filed April 25, 1925. Serial No. 25,758.

This invention relates to improvements in furnaces of the type illustrated in my Patent No. 1,530,321, dated March 17, 1925, wherein fine fuel is blown upwardly into a furnace chamber and burned in suspension, air in suitable volume to insure complete combustion being admitted at various points in the furnace. In such a furnace, it is important that the upward pressure of the air and gases in the furnace be sufficient to maintain the fuel in suspension without being so great as to blow unconsumed material out at the top of the furnace. The pressure of the air entering the furnace can be readily controlled by suitable valves, shown in the patent referred to; but it is also important to provide means for controlling the flow of gases passing from the furnace chamber to the stack, because the suction occasioned by the upward flow of gases in the stack affects the pressure of the air and gases in the furnace chamber. The purpose of the present invention is to provide means for stabilizing the pressure in the furnace chamber, and this is accomplished by conducting the gases issuing from the top of the furnace chamber downwardly through a large flue to a point at or below the level of the burners in the furnace chamber, and by providing at the outlet of this flue a valve or damper by which the draft through the furnace can be controlled. Thus, the columns of hot gases in the furnace chamber and in the downwardly extending flue tend to rise and balance one another, and by suitably adjusting the damper, to regulate the out-flow of gases to the in-put of air, the pressure in the furnace chamber can be maintained at the proper degree for holding the fuel in suspension in the chamber until it is consumed. Where the gases pass from the furnace to a stack, through a heating device such as a boiler, the stack will preferably be made short in order not to create a strong draft. The draft through the stack may be further controlled by the damper. Thus, in the normal operation of the furnace, only a sufficient natural draft through the stack will be maintained to draw the gases through the boiler or other heat-utilizing device.

In the accompanying drawing, I have shown a central vertical section through a furnace of the type illustrated in my prior patent, and also through a flue, stack and boiler.

In the drawing, α indicates a furnace chamber, circular in cross section and gradually enlarging from the bottom toward the top, and provided with inlet openings 1 at 60 various points in its height through which air may be injected by means of pipes or nozzles 2. At the bottom of the furnace is shown a pipe 3, having therein a worm conveyer 4 for feeding coal dust to a pipe 5, having a nozzle 6, extending upwardly through an opening at the bottom of the chamber. Air forced through a pipe 7 blows the coal upwardly into the chamber. The pipe 8 connects with a pipe 9, surrounding the 65 nozzle, and air admitted through the pipes 8 and 9 blows the fuel upwardly and holds it in suspension, all as explained in my patent referred to. In the lower part of the wall of the furnace chamber, a short distance above the fuel nozzle, suitable burners 10 are provided for igniting the fuel. After the fuel has become ignited and the furnace has become well heated, these burners may, if desired, be shut off and the incoming fuel 70 will then be ignited by the burning fuel and gases in the chamber; or the oil flow to the burners may be cut off and the air supply continued, to supply additional air to the furnace. The gases pass from the top of 75 the furnace chamber into a downwardly extending flue b , adjacent the furnace chamber. As shown, one wall 11 of the flue joins the upper end of the furnace chamber and extends over the chamber and thence 80 downwardly to a horizontal wall 12, and the opposing wall 13 of the flue extends from the top of the furnace chamber downwardly to the floor 14 of a settling chamber 15. The wall 12 is shown slightly higher than the 85 burners 10, and a gate or valve c , slidably in suitable vertical guideways 16, is adapted to serve as a damper for regulating the flow of gases from the flue b into the horizontal 90 passageway or settling chamber 15. The settling chamber 15 has an opening 17 in its 95 upper portion through which gases may flow to a heat-utilizing device, such as the tubular boiler 18, shown in the drawing, and from this device the gases flow to a stack 100 105 19, which is preferably made quite short and provided with a damper 20.

In the operation of the furnace, air and fuel are blown in at the bottom of the furnace chamber and the burners 10 are ignited, 110 and to supply the necessary oxygen for insuring combustion of all of the fuel, air in

regulated quantities is admitted to the furnace chamber through the pipes 2. A sufficient upward pressure of air is required to maintain the fuel in suspension, but this pressure must not be so great as to blow unconsumed fuel over into the flue b. The hot gases pass over into the flue b and thence downwardly, and by adjusting the gate c to the proper point, the outward flow of 5 gases from the flue b into the settling chamber and thence to the stack through the heat-utilizing device, may be regulated so as to maintain a practically constant pressure in the furnace chamber. The gases flow beneath the valve or damper c into the settling 10 chamber 15 and any ash carried there from the furnace will settle in this chamber and may be removed through a door 21. The stack 19, as stated, is preferably made short 15 so that the draft created in the stack will be slight and only sufficient to draw the gases through the heat-utilizing device 18. This draft may be regulated by the height 20 of the stack as well as by the damper 20. 25 Thus, with the arrangement described, the pressure in the combustion chamber can be maintained constant, whereas if the gases were allowed to flow freely through a stack to the atmosphere, the pressure at the top of 30 the combustion chamber would be lowered by a suction and would not be uniform, as the gases would take the shortest course out of the chamber. By the method herein described, a certain amount of back pressure 35 is maintained over the combustion chamber, and the pressure is substantially equal at all points across the top of the furnace, which is essential for maintaining the fuel in suspension until it is completely consumed.

40 What I claim is:

1. In a furnace for burning fine fuel in suspension, a vertically arranged combustion chamber of progressively increasing cross-sectional area from the bottom to the 45 top, means in the lower part of the chamber for blowing air and fuel upwardly therein, a flue, forming a continuation of said chamber and extending from the top thereof downwardly adjacent said chamber, said flue having an outlet in its lower part, a stack 50 connected to the flue for carrying off the gases from the furnace, and means for restricting the flow of gases through the apparatus.

55 2. In a furnace for burning fine fuel in suspension, a vertically arranged combustion chamber of progressively increasing cross-sectional area from the bottom to the top, means in the lower part of the chamber for blowing air and fuel upwardly therein, a 60 flue forming a continuation of said chamber

ber and extending from the top thereof downwardly, and a gate or damper at the lower end of said flue.

3. In a furnace for burning fine fuel in 65 suspension, a vertically arranged combustion chamber of progressively increasing cross-sectional area from the bottom to the top, means in the lower part of the chamber for blowing air and fuel upwardly therein, a 70 burner in the lower part of said chamber, a flue forming a continuation of said chamber and extending from the top thereof downwardly to a point below the burner, and a gate or damper controlling the outlet of said 75 flue.

4. In a furnace for burning fine fuel in suspension, a vertically arranged combustion chamber of progressively increasing cross-sectional area from the bottom to the top, 80 means in the lower part of the chamber for blowing air and fuel upwardly therein, a burner in the lower part of said chamber, a flue extending from the top of said chamber downwardly and having a lateral outlet 85 opposite the lower part of said chamber, and a valve or gate adjacent the upper wall of said outlet for restricting the size of the outlet.

5. In a furnace for burning fine fuel in 90 suspension, a vertically arranged combustion chamber of progressively increasing cross-sectional area from the bottom to the top, means in the lower part of the chamber for blowing air and fuel upwardly therein, a 95 burner in the lower part of said chamber, a flue extending from the top of said chamber downwardly and having a lateral outlet opposite the lower part of said chamber, a valve or gate adjacent the upper wall of 100 said outlet for restricting the size of the outlet, and a settling chamber connected to the flue through said outlet.

6. In a furnace for burning fine fuel in 105 suspension, a vertically arranged combustion chamber of progressively increasing cross-sectional area from the bottom to the top, means in the lower part of the chamber for blowing air and fuel upwardly therein, a 110 burner in the lower part of said chamber, a flue extending from the top of said chamber downwardly and having a lateral outlet opposite the lower part of said chamber, a valve or gate adjacent the upper wall of 115 said outlet for restricting the size of the outlet, a settling chamber connected to the flue through said outlet, and a relatively short stack connected to said settling chamber.

In testimony whereof I hereunto affix my signature.

JAMES POLLOCK.
